UNITED STATES PATENT OFFICE.

SAMUEL W. HILL, OF ROSS TOWNSHIP, ALLEGHENY COUNTY,
PENNSYLVANIA.

BRIDGE CONSTRUCTION.

SPECIFICATION forming part of Letters Patent No. 757,552, dated April 19, 1904.

Application filed August 20, 1902. Renewed February 23, 1904. Serial No. 194,880. (No model.)

To all whom it may concern:

Be it known that I, SAMUEL W. HILL, a citizen of the United States of America, residing in Ross township, in the county of Allegheny and State of Pennsylvania, have invented certain new and useful Improvements in Bridge Construction, of which the following is a specification, reference being had therein to the accompanying drawings.

10 This invention relates to certain new and useful improvements in bridge construction, and relates more particularly to that class wherein a structural iron or steel frame is employed in connection with a filling of cement concrete.

15 The present invention has for its object to provide a bridge construction that will take the place of stone arch-bridges, equaling the latter in strength and durability and materially reducing the cost of construction; furthermore, to provide a new and novel form of construction that will effectually overcome the unsafe conditions of a steel bridge, which becomes brittle when exposed to a low temperature and also subject to expansion and contraction due to the differences in temperature.

20 The invention further consists in the novel construction, combination, and arrangement of the parts comprising the structural steel or iron frame, all of which will be hereinafter more particularly described, and specifically pointed out in the claims.

25 In describing the invention in detail reference is had to the accompanying drawings, forming a part of this specification, and wherein like numerals of reference indicate like parts throughout the different views, in which—

30 Figure 1 is a side elevation of an arched bridge, partly in vertical section, showing my improved construction. Fig. 2 is a transverse sectional view partly broken away. Fig. 3 is a longitudinal vertical sectional view of the base, which rests upon a suitable foundation. Fig. 4 is a fragmentary top plan view of one of the girders and tie-plates. Fig. 5 is a similar view of one of the tie-plates. Fig. 6 is a side view thereof. Fig. 7 is an end

view of the same. Fig. 8 is a side view showing the manner of connecting the tie-plates together. Fig. 9 is an enlarged vertical sectional view of one of the girders.

35 In the drawings, 1 represents a suitable foundation, in which are anchored built-up structural steel or iron girders. These girders are formed of arched channel-bars 2, the flanges of which extend in opposite directions. These channel-bars are reinforced interiorly by angle-bars 3 and are suitably connected together. To the under face of the said channel-bars and angle-irons, upon which the girders are secured, is an arched plate 4, which plate is securely riveted to the lower or inner flanges of the channel-bars 2. The arched 40 plate extends slightly beyond the sides thereof and is adapted to receive the channel-bar tie-plates 5, which are riveted together at their flanges. These tie-plates serve to suitably space apart the built-up structural steel or iron 45 girders and complete the arched frame and form a base or support for the reception of the concrete and also forming the lower chord. The said channel-bars by reason of their flanges become mutually self-supporting and 50 form an ideal voussoir to the extent of the flanges. The said channel-bar tie-plates are securely riveted to the arched plates 4.

55 The reference-numeral 6 represents braces which extend at an angle over the upper faces of the channel-bars 2 and are securely riveted to said flanges and serve the purpose of the top chord, thereby leaving the built-up girders open to receive the concrete and also obtain an equal distribution of the stress 60 upon the girders; furthermore, permitting the girder to be securely embedded in the concrete, thereby excluding the same from the atmosphere.

65 The supporting or base plate 7 has secured thereto the lowermost flange of the channel-bar tie-plates, said base-plate secured to the stone, concrete, or other suitable foundation by means of anchor-bolts. Angle-irons 8 are also secured to the channel-bars 2, which give 70 strength and rigidity to the structure. The cement concrete is indicated by the reference-numeral 9 and forms the body portion of the

bridge, said cement concrete having formed thereon earth filling 10, and 11 indicates the ballast arranged upon the earth filling. 12 indicates the cross-ties of the rails.

- 5 It will be particularly observed that the entire strain upon the girders is edgewise, extending longitudinally, thereby greatly increasing their tensile strength when embedded in the concrete. It will also be noted that the 10 built-up girders may be formed of one, two, or more channel-bars suitably secured together, or they may be formed by combining the channel-bars and angle-irons or by employing Z-bars and I-beams, which may be 15 suitably riveted together, and that various other changes may be made in the details of construction without departing from the general spirit of my invention.

Having fully described my invention, what 20 I claim as new, and desire to secure by Letters Patent, is—

1. In an arched bridge, the combination of arched channel-bars and angle-irons forming girders, arched plates secured to the under 25 face of said girders, channel-bar tie-plates secured at their flanges arranged between said girders, and a filling of concrete embedding and surrounding said girders, substantially as described.
- 30 2. In an arched bridge, the combination of girders formed of channel-bars and angle-irons securely riveted together, arched plates secured to the under face of said channel and angle irons, channel-bar tie-plate secured to said 35 arched plates, braces extending and connecting the upper flanges of said channel-bars, and a filling of cement concrete embedding said channel and angle irons, substantially as described.
- 40 3. In an arched bridge, the combination of arched channel-bars, the flanges of which ex-

tend in opposite directions, arched angle-irons 45 interiorly reinforcing said steel bars, arched plates secured to the under face of said channel and angle irons forming girders, channel-bar tie-plates connected at their flanges and connected to said arched plates, in combination with a filling of cement concrete and earth, substantially as described.

4. In a bridge, the combination with the 50 arched channel-bars, of interiorly-arranged angle-bars secured to the said channel-bars, arched plates engaging and being secured to the under faces of the said channel-bars, and a filling of cement concrete. 55

5. The combination with the arched beams, of arched plates secured to the lower faces of the said beams, channel-bar tie-plates arranged between the said arched beams, said tie-plates being secured to the said arched plates, and a 60 filling of concrete or the like.

6. The combination with the beams, of plates 65 secured to the lower faces of the said beams, and extending beyond the edges thereof, tie-plates resting upon and secured to the extended portions of the said arched plates, and a filling, substantially as described.

7. The combination with the arched beams, of interiorly-arranged angle-bars secured to the said beams, bars secured to the upper edges 70 of the said beams, arched plates secured to the under faces of the said arched beams, and extending beyond the edges thereof, channel-bar tie-plates secured to the extended portions of the said arched plates, and a filling of concrete, 75 substantially as described.

In testimony whereof I affix my signature in the presence of two witnesses.

SAMUEL W. HILL.
